UNITED STATES PATENT OFFICE.

JACOB DÜRNHOLZ, OF KALK, GERMANY.

DRIVING DEVICE FOR PENDULUM-MILLS.

SPECIFICATION forming part of Letters Patent No. 787,737, dated April 18, 1905.

Application filed July 7, 1904. Serial No. 215,592.

To all whom it may concern:

Be it known that I, JACOB DÜRNHOLZ, a subject of the German Emperor, and a resident of Kalk, Germany, have invented certain new and useful Improvements in Driving Devices for Pendulum-Mills, of which the following is a specification.

This invention has for its object a driving device for one-pendulum mills which differs from the devices now in use for the same purpose (in which universal joints are used) by its great simplicity and reduction of friction, the sliding friction being replaced by a rolling friction.

The essential feature of the invention is that between two disks, of which one is driven from outside and the other is rigidly connected to the mill-pendulum, there is inserted near the periphery a rolling body of such a shape and size that the disk connected to the pendulum is brought into a position forming an angle with that of the other disk, and as soon as the latter is rotated the pendulum, which forms an acute angle with a perpendicular line and presses against the grinding-surface, is rolled around in a circle.

In Figures 1 to 5 of the accompanying drawings, in which similar letters refer to similar parts throughout the several views, different forms of construction of the invention are shown, all in vertical section.

Fig. 1 represents the whole pendulum-mill, with the new driving device in a longitudinal section. The pendulum-rod *h*, entering at the lower end the casing *a*, containing the grinding-surface, with the grinding-body *g* and the stirring-wings *r*, is provided at the upper end with a disk *b*, at the bottom surface of which there is affixed—by means of pins *f*, for instance—the upper winding of a strong screw-spring *c*, fastened at the bottom to the protecting-case *d* through screws *e* or any other means. At some distance above the disk *b* is provided a second disk *m*, provided at its bottom side near its periphery with a circular running-groove *l*, on the vertical shaft *i* of which disk there is fastened and pivotably journaled a driving device—for instance, a belt-pulley *k*. Between the disks *m* and *b* is inserted a suitable rolling

body—in this case a ball *n*, running in the circular groove *l*, and this ball is of such a size or the distance between the two disks is such that the windings of the spring *c* are compressed on one side, and the pendulum-rod 55 is pressed out of the vertical middle line of the grinding-surface *a* in a manner that the circumference of the grinding-body *g* exerts a strong pressure against the grinding-surface *a*. If the disk *m* is put in rotation, it rolls 60 the ball *n*. In consequence of the pressure on the same disk *b* is thereby also rotated and through the pressure of the spring *c* changes its position with regard to the axis of the grinding-surface. The latter consequently swings 65 in a circle. The pendulum *h* *g* in swinging around in a circle does not rotate on its own axis for the reason that it is connected to the spring *c* and the latter to the casing. The grinding-roller *g* does not, therefore, entirely 70 or only roll upon the grinding-surface *a*, but at each swing it slides upon the same for a certain distance. Such a movement of the pendulum has a double advantage. In the first place the grain after having been crushed, 75 as by a perfect rolling of the roller against the grinding-surface, is also pulverized, in consequence of the sliding, a circumstance which makes this new mill especially suitable 80 for fine grinding and prevents at the same time a baking together of a material which perhaps requires to be damped. It is evident that this kind of trituration must necessarily shorten and facilitate the grinding process. The bearings of the driving parts can, 85 moreover, in this way be perfectly and easily protected against outside influences, as the part of the pendulum-shaft projecting from the bearing may be firmly united with the frame of the machine by a movable girdle or 90 bolster *s* of india-rubber, leather, and so on, so that no dust can enter the bearing and no oil can run out into the grinding-space.

In the form of construction shown in Fig. 2 the pendulum-rod *h* is guided in a certain 95 manner by a bolster or neck bearing ring *o*, shiftable in the casing *d*, in which ring it rests by means of a rounded appendage or shoulder *p*. The ring *o* is therefore pressed with the disk *b* against *m*. In other respects 100

the working is the same as in the construction shown in Fig. 1.

In the construction according to Fig. 3 the rolling body *n* is not pressed by means of a spring between the disks *m* *b*, but by a weight. This is effected by providing on the casing *c* a U-shaped arm *v* with the bent upward, to which is joined a lever *t*, carrying a weight *q*. This lever resting on the end of the axle *i*, which is axially shiftable within narrow limits, presses the disk *m* against *b*. The pendulum-rod connected to the latter, and which is now movable in every direction in a fixed ball-bearing ring *o*, is again, through the rotation of *m*, caused to swing in a circle. Arm *t* can also be dispensed with if the weight of *m* *i* is sufficient to move the pendulum-rod out of its vertical direction.

Fig. 4 shows the case in which instead of a spring *c* the elasticity of an india-rubber ring *w* is used to effect a raising of the device pressing the disks together. In Fig. 5 finally is shown that instead of the ball *n* any other rolling device—for instance, an egg-shaped one *a*—may be used, which in this case, however, would require to be held by an axle *y*, bent into an angle and loosely pivotable in *i*,

which modification would not change the working nor the essential features of the driving device.

What I claim as my invention, and desire to secure by United States Letters Patent, is—

In a driving device for pendulum-mills, in combination, a grinding-pendulum *g* *h* resting on springs *c* by means of a disk *b* in the center over the grinding-surface and of a single rolling body *n* inserted between the disk *b* and another disk *m*, near the periphery, the disk *m* being rotated from the outside and the pendulum, being by springs pressed against the rolling body, is moved thereby out of its perpendicular central position into an inclined position with regard to the grinding-surface, which position is, in consequence of the rotation of the disk *m* and the rolling around in a circle of the rolling body constantly changed, substantially as and for the purpose set forth.

In testimony whereof I have signed my name to this specification in the presence of two subscribing witnesses.

JACOB DÜRNHOLZ.
